CLAIM

The ornamental design for a stereographic virtual head adapter for mobile graphical devices, as shown and described.

DESCRIPTION

FIG. 1 is a front elevation view showing our new design; FIG. 2 is a back perspective view thereof; FIG. 3 is a right side elevation view thereof; FIG. 4 is a left side elevation view thereof; FIG. 5 is a top plan view thereof; FIG. 6 is a bottom plan view thereof; FIG. 7 is a front, right side perspective view thereof; FIG. 8 is a back, right side perspective view thereof, wherein the back, left side perspective view is a mirror image thereof; FIGS. 9-10 each depict a front, right side perspective view thereof, wherein the stereographic virtual head adapter for mobile graphical devices is in an open configuration; and, FIG. 11 is a front, right side perspective view thereof, wherein the stereographic virtual head adapter for mobile graphical devices is in a closed configuration. An optional mobile graphical device is shown in broken lines in FIGS. 9-11 for environmental purposes only and forms no part of the claimed design.
